(57) **CLAIM**

The ornamental design for a pocket knife, as shown and described.

DESCRIPTION

FIG. 1 is a right side view showing our new design;

FIG. 2 is a left side view thereof;

FIG. 3 is a top plan view thereof;

FIG. 4 is a bottom plan view thereof;

FIG. 5 is a front elevational view thereof; and,

FIG. 6 is a rear elevational view thereof.

The broken line showing of a knob in FIGS. 1-5 is for illustrative purposes only and forms no part of the claimed design.

UNITED STATES PATENT AND TRADEMARK OFFICE
CERTIFICATE OF CORRECTION

PATENT NO. : Des. 529,363 S
APPLICATION NO. : 29/228809
DATED : October 3, 2006
INVENTOR(S) : Scott D. Freer and John A. Sullivan, Jr.

Page 1 of 2

It is certified that error appears in the above-identified patent and that said Letters Patent is hereby corrected as shown below:

In the attached drawing Figures:

In Fig. 1 a shade line should extend along the outer edge of the handle, and there should not be shading in the cutout of the handle.

In Fig. 2 a shade line should extend along the outer edge of the handle.

In Fig. 3 there should be horizontal lines indicating the cutout in the handle.

In Fig. 5 there should be shade lines on the outer edges of the handle.

In Fig. 6 there should be shade lines on the outer edges of the handle, as shown.

Signed and Sealed this

Third Day of April, 2007

A handwritten signature in black ink, appearing to read "Jon W. Dudas". The signature is written in a cursive style with a large, stylized "J" and "W".
